ADJUSTABLE STEP FOR AUTOMOBILE RUNNING BOARDS

Filed May 27, 1922

UNITED STATES PATENT OFFICE.

JOSEPH DISCH AND JOHN G. FRESE, OF ST. LOUIS, MISSOURI.

ADJUSTABLE STEP FOR AUTOMOBILE RUNNING BOARDS.

Application filed May 27, 1922. Serial No. 564,024.

To all whom it may concern:

Be it known that we, JOSEPH DISCH and JOHN G. FRESE, citizens of the United States, and residents of St. Louis, Mo., have 5 invented certain new and useful Improvements in an Adjustable Step for Automobile Running Boards, of which the following is a specification.

This invention relates to improvements in 10 an adjustable step for automobile running boards, and has for its object a step composed preferably of two-parts arranged to be fitted together so as to accommodate a narrow as well as a deep step; thus allowing 15 the rear portion to fit snug up against the machine frame and the front edge to snugly contact with the front edge of the running board.

By means of the sliding feature the step 20 can be adjusted to fit the running board in the event the same should become out of alignment and at the same time avoiding a space between the rear and the frame work or body of the machine.

25 The step is made out of durable light material the surface of the plate or foot section provided with a ridge or uneven or irregular surface so as to prevent slippage. The extreme front is provided with a scraper by 30 which mud can be removed from the shoe, and the step in general ornamented to suit convenience in order to make a neat and unique appearance when placed in position on the running board.

35 Figure 1, is a perspective view of our invention shown in position on the running board.

Fig. 2, is a top plan view.

Fig. 3, is a side view.

40 Fig. 4, is a sectional view taken on the line 4—4 of Fig. 2.

Fig. 5, is a detail perspective view of our improved adjustable step detached from the running board.

45 In the general construction of our invention we provide a step preferably composed of two sections A and B. The section A is preferably termed a foot-plate, the surface of which is provided with elevations or corrugations 6 to provide a roughened surface 50 for the foot so as to prevent slippage.

This plate is provided with apertures 7 through which screws or the like are inserted for fastening the plate to the running board 8.

The front surface of the plate is provided with a downwardly extending flange 9 which is suitably bent to form a scraper 10. This is preferably designed for removing mud from the shoe before entering the automobile. 60

The frame which comprises the plate is provided with a cut-away portion 11 which fits over the finishing strip generally attached to the front edge of the running board, and the bottom of the plate is provided with suitable projections 12 which rest upon the running board and hold the plate in firm position. 65

The section B is the sliding or adjustable section, the rear edge 13 is to be brought in 70 communication or contact with the frame or body of the machine, and it is provided with apertures 15 through which fastening devices are inserted for attaching the same to the running board. This section is provided 75 with a flange 16 which fits over the side edge of the plate A so as to make a close joint of neat appearance.

This adjusting plate B may be ornamented to suit the convenience and at the 80 same time this section acts as a toe plate to prevent the toe of the shoe from marring or scratching the polished surface of the machine frame or body.

The essential feature of this structure of 85 plate is to make the same of two sections to be adjusted to accommodate any width of running board.

Having fully described our invention 90 what we claim is:

A step of the character described comprising an ornamented foot plate having a front contacting flange, a scraper formed by said flange, said plate attached to the running board and a toe section slidably mounted on said plate and brought in contact with the body of the machine, thereby taking the full depth of the running board, substantially as specified. 95

In testimony whereof, we have signed our 100 names to this specification, in presence of two subscribing witnesses.

JOSEPH DISCH.
JOHN G. FRESE.

Witnesses:

ALFRED A. EICKS,
B. M. MAIME.
